DESIGN FOR A SWEATER ENSEMBLE

Maxwell W. Elkind, New York, N. Y.

Application July 27, 1938, Serial No. 78,755

Term of patent 3½ years

To all whom it may concern:

Be it known that I, Maxwell W. Elkind, a citizen of the United States of America, residing in city of New York, county of New York, and State of New York, have invented a new, original, and ornamental Design for a Sweater Ensemble, of which the following is a specification, reference being had to the accompanying drawing, forming part thereof.

Fig. 1 is a front view of a sweater ensemble showing my new design.

Fig. 2 is a rear view thereof.

Fig. 3 is a front view of the sweater portion without the suspenders and bottom border. The rear view of the sweater portion is conventional.

The design is characterized by the specific suspenders together with the bottom border in combination with the sweater as shown.

I claim:

The ornamental design for a sweater ensemble, substantially as shown and described.

MAXWELL W. ELKIND.
